UNITED STATES PATENT OFFICE.

JOHN J. CALLOW, OF CLEVELAND, OHIO.

GRAINING.

SPECIFICATION forming part of Letters Patent No. 605,244, dated June 7, 1898.

Application filed November 13, 1896. Serial No. 611,944. (No model.)

To all whom it may concern:

Be it known that I, JOHN J. CALLOW, a citizen of the United States, residing in Cleveland, in the county of Cuyahoga and State of Ohio, have invented certain new and useful Improvements in Graining, of which the following is a specification.

This invention relates to a new and useful method of graining surfaces of wood and the like, and it also contemplates certain new and useful improvements in graining-combs, all of which will be specifically described in the accompanying specification and illustrated in the drawings, in which—

15 Figure 1 is a plan view of a flexible rubber pad provided with concentric and curved or arc-shaped ribs slightly raised on the surface. Fig. 2 is a similar view with the ribs shown larger or coarser. Fig. 3 is a plan view of a 20 substantially square pad having circular rings increasing in diameter from the center to the sides of the pad. Fig. 4 is a view of my improved blending device. Figs. 5 and 6 represent methods of using the pads and a 25 regular steel graining-comb now in common use in practicing my process.

In Fig. 1 letter A represents a common center of the arc-shaped ribs shown therein, while letters B and C in Figs. 2 and 3 represent similar centers of curvature.

While I have shown the pads in Figs. 1, 2, and 3 as provided with concentric arc-shaped ribs, I wish it understood that the surfaces of these pads may be provided with other configurations without departing from the spirit of my invention.

The pads are usually constructed of rubber and are quite flexible, so that when grasped by the hand they may bend to a certain extent, as shown in Fig. 5. These pads, however, may be constructed of other material than rubber—such, for instance, as paper or leather—with equally good results.

In Figs. 1 and 3 the arc-shaped ribs are shown as substantially the same in width, while in Fig. 2 the ribs are shown as somewhat broader. The purpose of having the ribs of varying widths is to produce graining effects of different aspects when the pads are 50 drawn over a surface coated with color.

E in Fig. 4 represents a graining-comb having the teeth F, provided with the hooked

ends G. Stretched over the graining-comb are the rubber bands H, whose purpose is to give to the comb-teeth a certain resiliency 55 and softness of action when passed over the work not possessed by the uncovered teeth when used alone. In Fig. 4 it will be noticed that two of the rubber bands H therein shown are illustrated as stretched over the teeth of 60 the comb, while a third rubber band is shown detached therefrom. It may be here remarked that the purpose of my improved graining-comb is similar to that of all graining-combs—*i. e.*, to give the freshly-grained work a cer- 65 tain mottled or streaked appearance whenever the comb is drawn over the surface thereof.

Having now specifically described the various devices used in carrying out my improved method of graining, I will now proceed 70 to describe in detail the manner of practicing such method.

The surface to be grained is first coated with any desired coloring-matter. Then any one of the pads is grasped by the hand and 75 drawn over the freshly-colored surface, as shown in Fig. 5. Coincident with the movement of the pad over the said colored surface the operator should draw an ordinary steel graining-comb over the top surface of the 80 graining-pad with varying pressure and at a speed differing from that at which the said graining-pad is being moved. This conjoint action of the pad and comb will produce a grained surface similar to that shown in Figs. 85 5 and 6. Said grained surface is subsequently finished by striking the same against the grain with the rubber-covered blending-comb, as shown in Figs. 4 and 6. Such a procedure will give the grained surface a mottled or 90 streaked appearance.

It will be noticed in Fig. 5 that a graining-comb of ordinary construction is illustrated in connection with the pad. Such combs as my improved comb illustrated in Fig. 4 may 95 be used with equal facility, the specific object, however, of my rubber-covered blending-comb being its adaptability for the finishing of the grained surface produced by my new process, as illustrated in Fig. 6.

Having now fully described my invention, what I claim, and desire to secure by Letters Patent of the United States, is—

1. The method of graining in imitation of

wood, which consists in coating the surface thereof to be grained, with graining color then drawing over said colored surface, a flexible pad provided with concentric lines 5 on its under side, and at the same time drawing a grainer's comb over the top surface of said pad at a speed different from that at which the pad is moving, substantially as described.

- 10 2. The method of graining in imitation of wood, which consists in coating the surface thereof to be grained, with graining color then drawing over said coloring surface a flexible pad provided with concentric lines on 15 its under side, and at the same time drawing a grainer's comb over the top surface of said

pad at a speed different from that at which the pad is moving, and finally striking the said grained work against the grain thereof with a flexible blending-comb, substantially as described and for the purpose herein set forth. 20

3. As a new article of manufacture, a blending-comb, provided with flexible teeth, a hook on the end of each of said teeth, and a band or web of rubber tightly stretched around 25 said comb and covering said hooked teeth, substantially as described.

JOHN J. CALLOW.
